US0D1101781S

(12) **United States Design Patent** (10) **Patent No.:** **US D1,101,781 S**
(45) **Date of Patent:** **** Nov. 11, 2025**

(54) **DISPLAY SCREEN OR PORTION THEREOF WITH GRAPHICAL USER INTERFACE**

(71) Applicant: **Samsung Electronics Co., Ltd.**, Suwon-si (KR)

(72) Inventor: **Ahreum Han**, Suwon-si (KR)

(73) Assignee: **Samsung Electronics Co., Ltd.**, Suwon-si (KR)

(**) Term: **15 Years**

(21) Appl. No.: **29/936,915**

(22) Filed: **Apr. 11, 2024**

(30) **Foreign Application Priority Data**

Jan. 3, 2024 (KR) 30-2024-0000285

(51) LOC (15) Cl. **14-04**

(52) U.S. Cl.

(57) **CLAIM**

The ornamental design for a display screen or portion thereof with graphical user interface, as shown and described.

DESCRIPTION

The sole FIGURE is a front view of a display screen or portion thereof with graphical user interface showing my new design.

The outermost perimeter broken line in the FIGURE depicts a display screen or portion thereof and forms no part of the claimed design.

The grayscale tones shown in the drawings illustrate a contrast in appearance.

1 Claim, 1 Drawing Sheet
